VERTICALLY VIBRATING DIAPHRAGM
PULP SCREENJames R. Dunbar, Woodstock, New Brunswick,
Canada, assignor to Thomas L. Dunbar, Mont-
real, Quebec, Canada

Application November 21, 1936, Serial No. 112,155

8 Claims. (Cl. 92—32)

This invention relates broadly to improvements in pulp screens and relates more particularly to flat screens in which the pulp stock is caused to flow over slotted plates through which acceptable stock passes, the passage of stock being induced and clogging of the screens minimized or prevented by the vibration of diaphragms located below the screen plates.

The mechanisms at present in general use to 10 vibrate the diaphragms are mechanically driven against the action of heavy return springs and therefore consume much power besides being subject to rapid wear and requiring much lubrication. In many such devices the power stroke 15 thrusts the diaphragms toward the screens and the reverse movement which induces stock flow through the screens is dependent on the action of heavy springs, with result that the speed and amplitude of downward movement cannot be accurately controlled.

The primary object of my invention is to provide means for vibrating the diaphragms of flat pulp screens which will consume only a small amount of power and lubricant and in which 25 wear will be reduced to a negligible amount.

A further object is the provision of a diaphragm vibrating mechanism in which the driving power is directly applied to effect downward as well as upward movement of the diaphragms, 30 so that the speed and amplitude of both movements will be accurately controlled.

A still further object is the provision of a drive mechanism of simple, durable and inexpensive construction having a small number of moving 35 parts of such character and arrangement as to substantially eliminate the chance of accidental injury to an attendant.

Various other objects and advantages of the invention may be ascertained from the following 40 description and the accompanying drawings.

The invention consists essentially in the provision of hydraulic actuating means for each screen diaphragm, the said means being connected in pairs by rocking levers and the means of each pair being hydraulically powered alternately in such wise that the hydraulic power applied to raise the screen diaphragm associated with one means of the pair is applied through the rocking lever to positively depress the screen diaphragm associated with the other means of the pair. Any suitable type of control valve is provided and as many pairs of hydraulic actuating means as desired are connected to a single valve.

In greater detail, the invention consists in the 55 features and combinations of features herein de-

scribed or disclosed in the accompanying drawings together with all such modifications thereof and substitutions therefor as are within the scope of the appended claims.

In the drawings which illustrate one embodiment of the invention but to the details of which the invention is not limited as other modifications are possible and contemplated—

Fig. 1 is a front elevation partly in vertical section illustrating the application of my invention to a flat pulp screen of conventional design. 10

Fig. 2 is an end elevation of the structure shown in Figure 1.

Fig. 3 is a plan view of the diaphragm vibrating mechanism. 15

Fig. 4 is a vertical sectional view of one of the hydraulic actuating means of Figure 1 on an enlarged scale.

Fig. 5 is a vertical cross sectional view of the control valve on the line 5—5 of Figure 3. 20

Referring more particularly to the drawings, 11 designates a screen box or trough, the bottom of which is formed of a series of flexible diaphragms 12 supported in the usual way by the sides of the trough and by cross bearers 13 which also support the slotted screen plates 14. The pulp stock to be screened is fed into the trough above the plates 14, flows through the plate slots and is removed through the space between the plates and diaphragms in the well known manner. The construction illustrated embodies six 25

diaphragms but it will be understood any even number of diaphragms may be used. The box is mounted on any suitable number of frames 15 which are connected by a longitudinal beam 16 30

of sufficient rigidity to adequately support the vibrating mechanism. The central part of each diaphragm 12 is clamped between upper and lower plates 17, the latter of which is rigidly connected to a depending push rod 18. 35

According to this invention, a series of hydraulic actuating means 19 are mounted on the beam each centrally under a diaphragm and operatively connected to the push rod thereof. The 40

push rods are connected in pairs by rocking levers 20 pivotally mounted midway between their ends on any suitable supports such as brackets 21 secured to and projecting upwardly from the beam 16. The connections between the push rods and 45

rocking levers comprise cross pins 22 on the push rods rotatable in blocks 23 slidably engaging in slots 24 in the ends of the rocking levers. While the arcuate movement of the lever ends is very slight and could be compensated for by providing 50

slightly oversize holes in the levers to receive the 55

cross pins 22, it is preferred to use the sliding block arrangement as it eliminates lost motion and consequent pounding, but it will be understood the blocks may be dispensed with and the pins engaged directly in slots of suitable size.

The hydraulic means designated by the numerals 19' to 19⁶ may take a variety of forms but that now preferred consists of a series of diaphragm casings each comprising lower and upper 10 annular flanges 25 and 26 respectively, between which a flexible diaphragm 27 is claimed by bolts 28 which may serve also to attach the flanges to the beam 16. The lower flange 25 has connected to it a supply pipe 29. The upper flange is provided with an upstanding hollow neck 30 through which the lower end of a push rod 22 passes and is connected to the diaphragm by upper and lower clamping plates 31 mounted on the push rod and secured by a nut 32. The neck is preferably provided with a bushing 33 of bronze or other suitable material for engagement with the push rod. The space within each neck above the diaphragm may be filled with an elastic substance 34, such as sponge rubber, to support the exposed portion of the diaphragm.

For the supply of a motive liquid under pressure to the casings 19'—19⁶ and for the discharge of the liquid, there are provided a pair of supply mains 35 and 36, a pair of discharge mains 37 and 38 and any suitable valve mechanisms for controlling the flow of liquid in said mains and designated as a whole by the numeral 39. Each of said mains is connected to every second casing of the series by means of branches 40 and 41 directly cross-connecting the supply and discharge mains and to which the individual supply pipes 29 of the casings are connected. Thus, the supply main 35 is directly cross-connected to the discharge main 37 by branches 40 to which the supply pipes of casings 19', 19³ and 19⁵ are connected. Similarly, the supply main 36 is cross-connected directly to the discharge main 38 by the branches 41 to which the supply pipes of casings 19², 19⁴ and 19⁶ are connected. The two supply mains may be connected to a single inlet 42 through which they are supplied with liquid under pressure and the two discharge mains may be connected to a single outlet 43.

The valve mechanism comprises what is in reality a valve in each main and any suitable means for operating the valves in predetermined relation. As illustrated, the two supply valves are formed in one and the two discharge valves in one and all are enclosed in a single casing, but the arrangement may be otherwise. The mechanism illustrated comprises a valve casing 44 inserted in and common to all the supply and discharge mains and containing a pair of rotatable valve members 45 and 46, pertaining respectively to the supply and discharge mains and fixed on a shaft 47 provided with any suitable sort of drive means, such as a pulley 48.

The valve member 45 is provided with a pair of diametrically disposed flow passages 49 and 50 arranged at right angles to one another and adapted to selectively align with the supply mains. The valve member 46 is provided with a pair of flow passages 51 and 52 arranged similarly to the passages 49 and 50 and adapted to selectively align with the discharge mains. The two valve members 45 and 46 are so relatively arranged on the shaft that the supply passages 49 and 50 are respectively parallel, or substantially so, with the discharge passages 52 and 51.

The operation of the device is as follows:—

In the position illustrated, valve passage 49 is in alignment with supply main 35 feeding casings 19', 19³ and 19⁵, while the valve passage 51 is at right angles to and closes the discharge main 37 pertaining to these casings, so that fluid under pressure is admitted to but cannot escape from these casings. The diaphragms in these casings and the push rods connected thereto are moved upward. At the same time, valve passage 50 is at right angles to supply main 36 feeding casings 19², 19⁴ and 19⁶, while the valve passage 52 is in alignment with the discharge main 38 draining these casings, so that fluid under pressure is excluded from these casings while fluid therein is permitted to escape. The aforesaid upward movement of the push rods of casings 19', 19³ and 19⁵ is communicated through the rocking levers 20 to the push rods of casings 19², 19⁴ and 19⁶ respectively and depresses the same so that liquid is expelled from these casings. Motive power is applied to rotate the valve members 45 and 46 and, upon a quarter rotation of the valve members, the conditions above described are reversed, namely, the valve passage 49 is at right angles to supply main 35, thus excluding fluid 25 pressure from casings 19', 19³ and 19⁵, while the valve passage 51 is in alignment with the discharge main draining these casings so that liquid previously admitted may escape now. At the same time, valve passage 50 is in alignment with supply main 36 serving casings 19², 19⁴ and 19⁶ and valve passage 52 is at right angles to the discharge main 38 draining these casings, so that fluid under pressure is admitted to but cannot escape from these casings. The pressure now 30 forces up the diaphragms and push rods of casings 19², 19⁴ and 19⁶ and this movement is communicated through the rocking levers 20 to depress the previously elevated push rods and diaphragms of casings 19', 19³ and 19⁵ and expel 40 liquid from them the liquid previously admitted. On a further quarter rotation of the valve members the condition first described is restored. By continuously rotating the valve members liquid will be alternately admitted to and released from each of the casings, thus causing reciprocating movement of the push rods and vibration of the screen diaphragms connected thereto.

As the reciprocating movement of the push rods is only a fraction of an inch and as the supply mains and other flow passages are quite large relatively to the casings, there is very little fluid friction and very little actual flow of liquid. The system is constantly full of liquid and, as the flow necessary to accomplish each vibration of the diaphragms is only a small fraction of the liquid in the system, the motive action is more one of intermittently applying pressure than of moving the liquid body. This enables a very rapid vibration of the screen diaphragms to be 60 realized.

The rate of vibration is controlled by the rate of rotation of the valves. If desired, the discharge valves may be given a slight lead over the supply valves so that a cushioning effect will 65 result after the manner well known in steam engine practice. This relative setting of the valves will also serve to limit the amplitude of reciprocating movement of the push rods and diaphragms. While the flow passages through 70 the valves are illustrated as cylindrical and while there is shown considerable dead space at the circumference of the valves, it will be understood these passages may be of other suitable shape and that the dead space may be proportionately 75

more or less than shown, according to the results desired, as will be well understood by valve designers.

While diaphragms are shown at the lower ends of the push rods, it will be understood similar results will be obtained if the push rods constitute or are provided with pistons sliding in the casings 19' to 19⁶, but the use of diaphragms is preferred as it avoids the mechanical friction incident to liquid tight fits between pistons and cylinders and thereby reduces the power consumption if the device is served by a pump. The push rods are preferably easy running fits in their bushings and therefore substantially frictionless. An easy fit is also desirable as it will leak and give notice if the associated diaphragm 27 should be ruptured.

Having thus described my invention, what I claim is:

20 1. In a pulp screening machine, a series of screening diaphragms, a push rod connected to each diaphragm, a fluid pressure actuated operating means for each push rod, rocking levers pivotally mounted intermediate adjacent push rods and operatively inter-connecting them and their associated operating means in pairs whereby the operating means of each pair influence one another alternately and means for alternately admitting liquid under pressure to and releasing liquid from each said operating means, the admission of liquid to one operating means of each pair occurring simultaneously with release of liquid from the other means of each pair.

25 2. In a pulp screening machine, a series of screening diaphragms, a push rod connected to each diaphragm, a fluid pressure actuated operating means for each push rod, means for admitting liquid under pressure to alternate operating means of the series simultaneously and means 30 operating coincidently with said admitting means for releasing liquid from the remaining means simultaneously and mechanical means interconnecting said push rods and their associated operating means in pairs and adapted upon actuation of one means of each pair by liquid under pressure to reversely actuate the other means of each pair for expulsion of liquid therefrom.

35 3. In a pulp screening machine, a series of screening diaphragms, a push rod connected to each diaphragm, pivotally mounted rocking levers pivotally connected to the push rods and connecting them in pairs, an operating chamber for each push rod in which the rod is reciprocable, means for alternately admitting liquid under 40 pressure to and releasing liquid from each said operating chamber for reciprocation of the push rods, and flexible diaphragms connected between the ends of the push rods and the walls of the respective operating chambers and constituting sealing means to prevent escape of liquid between the push rods and chamber walls.

45 4. In a pulp screening machine, a series of screening diaphragms, a push rod connected to each diaphragm, a fluid pressure actuated operating means for each push rod, a supply main and a discharge main each connected to each alternate operating means of the series, a second supply main and a second discharge main each connected to each of the remaining operating means 50 of the series, and valve means for admitting liquid under pressure to said supply mains alternately and for releasing liquid from said dis-

charge mains alternately, the release of liquid from each discharge main being simultaneous with admission of liquid to the associated supply main, and pivotally mounted rocking levers pivotally connected to the push rods and connecting the push rods associated with the first supply main with the push rods associated with the second supply main.

5. In a pulp screening machine, a screening trough including screens and a row of diaphragms forming the bottom of said trough, a frame supporting the trough including a beam paralleling the row of diaphragms, a row of hydraulic chambers mounted on said beam and severally aligned with the diaphragms, push rods connected to the diaphragms and slidably entering the hydraulic chambers, separate supply and discharge mains connected to said hydraulic chambers, powered valve means for intermittently admitting liquid under pressure to a supply main and simultaneously releasing liquid from an associated discharge main, whereby each of said chambers is intermittently powered, brackets mounted on said beam, rocking levers pivotally mounted on said brackets and connected to adjacent push rods and operatively connecting the push rods in pairs whereby the admission of fluid to one chamber of each pair serves to expel fluid from the other chamber.

6. In a pulp screening machine, a series of screening diaphragms, an hydraulic operating chamber for each diaphragm, a push rod connected to each diaphragm and having reciprocating engagement in the associated hydraulic chamber, a supply main and a discharge main, 35 branches directly connecting said mains together at intervals, pipes leading from said branches severally to alternate hydraulic chambers, a second supply main and a second discharge main, branches directly connecting said second mains 40 together at intervals, pipes leading from said last mentioned branches severally to the remaining hydraulic chambers and valve means for admitting liquid under pressure to said supply mains alternately and for simultaneously releasing liquid 45 from the associated discharge mains; and pivotally mounted rocking levers pivotally connected to the push rods and connecting the push rods of said alternate chambers with the push rods of the remaining chambers.

7. In a pulp screening machine, a pair of screening diaphragms, a single acting hydraulic chamber associated with each diaphragm, a push rod connected with each diaphragm and having reciprocating engagement in the associated 55 chamber, means for admitting liquid under pressure to the chambers alternately and for releasing liquid from the chambers alternately, the admission to each chamber synchronizing with the release from the other chamber, and a rocking lever pivotally mounted intermediate of and connected to said push rods whereby the operation of each push rod by admission of liquid to the associated chamber serves to operate the other push rod for expulsion of liquid from the other chamber.

8. In combination with structure according to claim 7, a diaphragm in each chamber operatively connected to the wall of the chamber and to the push rod therein and forming sealing means between the push rod and chamber.

JAMES R. DUNBAR.
